UNITED STATES PATENT OFFICE.

THOMAS R. COOK, OF PITTSBURGH, PENNSYLVANIA.

DESIGN FOR A CONNECTOR FOR A SECONDARY BATTERY.

56,738.

Specification for Design.

Patented Dec. 14, 1920.

Application filed August 10, 1920. Serial No. 402,691. Term of patent 14 years.

To all whom it may concern:

Be it known that I, THOMAS R. COOK, a citizen of the United States, residing at Pittsburgh, in the county of Allegheny and State of Pennsylvania, have invented a new, original, and ornamental Design for Connectors for Secondary Batteries, of which the following is a specification, reference being had to the accompanying drawing, forming part thereof.

In the drawing:

Figure 1 is a top plan view of the connec-

tor; Fig. 2 is a side plan view of the connector shown in Fig. 1, and Fig. 3 is a bottom plan view of said connector.

I claim:

The ornamental design for a connector for a secondary battery, as shown.

THOMAS R. COOK.
